UNITED STATES PATENT OFFICE.

HERMANN JÄNISCH, OF LIMBACH, GERMANY, ASSIGNOR, BY MESNE ASSIGNMENTS, TO LEWIS INVISIBLE STITCH MACHINE CO., OF ST. LOUIS, MISSOURI, A CORPORATION OF MAINE.

SEWING MACHINE.

Application filed December 14, 1922. Serial No. 606,766.

My invention relates to blind-stitch sewing machines, and has for its general object to provide a simple, efficient, high-speed blind-stitch machine capable of, and especially adapted for, working upon very thin elastic materials, such as the thin fabrics of silk and of other materials used in gloves and undergarments, and forming a chain stitch of great elasticity so that stretching of the seamed materials will not break the thread.

More particularly my invention provides, in coordination with a suitable feeding mechanism of a type especially adapted for such work as above stated, a simple and efficient stitch-forming mechanism, including a looper mechanism especially adapted to handle the thread in conjunction with cloth feeding mechanism of the character provided.

In the drawings wherein I have illustrated a single embodiment of my invention for purposes of disclosure, but without intent to limit my invention to the details thereof, Figure 1 is a front elevation, with parts broken away; Figure 2 is an end elevation with parts broken away; Fig. 3 is a plan view; Fig. 4 is an inverted plan view; Fig. 5 is a plan detail of the stitch forming parts, as viewed on the section line 5—5 of Fig. 2; Fig. 6 is a front elevation of said parts with the presser-foot in section and Figs. 7 to 11 are diagrams of operation of the looper mechanism.

The base 15 houses the main shaft 16 from which all driven parts are operated, this base being surmounted by a hollow work-platform or table 17 by which the work-presenting and feeding mechanism is carried. Preferably this table is relatively short, or narrow in the direction of length of the machine, and the work-presenting means may be located close to the inner edge of the table as shown in Fig. 1. For the fine character of work contemplated, the work-presenting and feeding mechanism should be such as constantly to present a bend in the work, for penetration by the needle, always at the same level, and at this end I preferably employ a narrow feed wheel 18, sharply ridged or double-beveled at its periphery, mounted on a positively-positioned shaft 19 with its uppermost peripheral sector projecting through an opening 20 in the table.

For feeding purposes the beveled edges of 55 the wheel may be toothed or serrated as at 21, and in operation the wheel may be given unidirectional step by step rotation for feeding purposes.

With the specific mechanism for imparting work-feeding rotation to the wheel the present invention is not concerned, but one effective operating mechanism for the wheel is illustrated as comprising, generally, a frictional feed band 22 embracing a hub 65 23 of the wheel, this band being split and provided with terminal lugs 24 and 25. Lug 24 is connected by links 26 and 27 to a pivot pin 28 on anchoring bracket 29, the vertical link 27 having a lever arm 30 connected to eccentric strap 31 for an eccentric 32 on the main shaft 16. The other lug 25 is perforated to slidably receive pin 34 of eccentric strap 35 for an eccentric 36 mounted on a main shaft, and the pin 34 has a spring 37 interposed between its head and the lug 25. This provides one suitable means for unidirectional rotation of the feed wheel through a friction clutch that is alternately tightened and loosened, and is given 70 an oscillating displacement around the wheel-axis 19 by the positive action of the suitably-timed eccentrics, but other suitable feed mechanisms may be substituted, if desired. 75

As far as the present invention is concerned, it is desirable that the plane of presentation of a sharp band of the work be unchanging, and that the bending device be located close to the inner side of the 90 work-table, and for simplicity it is desirable to employ the feeding wheel as the bending instrumentality.

The stitch-forming mechanism, arranged to work wholly from above the work-presenting means, has its actuated parts carried by the overhanging arm 40 projecting from a vertical post 41, the overhead frame being preferably supplemented by a central bracket 42 to support the needle-bar and a portion 95 of the looper. The slender needle 44 is carried by a horizontally-arranged, reciprocating needle bar 45 and is slidably mounted in the forked lower end of bracket 42. The needle, in its reciprocation, travels in guided 100 relation to a presser-foot 46 that cooperates with the feed wheel, and is slotted as at 47 (Figs 5 and 6) so that the feed wheel may 105

present a bend of the work through this presser-foot work-opening. With the needle there cooperates a main looper-member or looper-hook 48 arranged for oscillation in a horizontal plane, parallel with and slightly above the line of needle travel. And with the main looper element there cooperates a secondary looper element or loop-holder 49, vibratable in a plane substantially at right-angles to the plane of operation of the main looper.

For driving all of these working parts from the main shaft two eccentrics 50 and 51 are provided, the former working the needle bar and the main looper member, and the latter operating the secondary looper member. Eccentric 50 has its strap 52 connected by stem 53 and universal ball-joint 54 with the bell crank arm 55 of a double lever 56, one operating arm of which, indicated at 57, extends down within the post 41 for connection through link 58 with a bracket 59 on the reciprocable needle-bar. This operating lever for the needle-bar also carries the take-up finger 60 that projects through a slot 61 in the base of the post. The other arm, 63 of the double lever 56, extends up and above the frame arm 40, and at its upper end has pivotal connection 64 with a link 65 that imparts motion to the laterally oscillatable main-looper member 48.

The presser-foot 46 is mounted on vertical presser-bar 67, impelled by spring 68 toward the work-presenting feed wheel, and the bar 35 may be raised against the tension of its spring by a knee lift lever 69 that acts against a lifter bar 70 arranged in the head of arm 40 so that its pin 71, extending into connection with the presser-bar, may elevate 40 the latter when the knee lift lever is depressed. The presser-bar correspondingly has a pin 72 working between collars 73 on the vertical rock-shaft of the main looper member, so that the latter may be raised and 45 lowered with the presser foot. The narrow foot proper, 46, is angularly grooved along its underside, corresponding with the contour of the feed-wheel periphery, and is formed with a grooved needle-guiding projection 74, 50 the groove of which is narrow enough to well steady the needle and finds continuation at 74' (Fig. 5) on that side of the presser-foot from which the needle enters the work. For very fine work of the character particularly contemplated, a very slender needle 55 will be employed, and this extremely accurate guidance, in conjunction with the constantly regulated presentation of the bend of the work, insures great accuracy in the production of a uniform and blind seam.

The oscillatory looper member 48 is preferably a curved hook having a point 80 to engage the needle thread loop, such point terminating at a shoulder 81 which will serve 60 to carry the loop, and such looper hook is ar-

ranged to swing in a horizontal plane directly above the needle path through a range of travel substantially as indicated, as to limits, by Figures 7 and 10; that is to say, the point starts from that side of the needle which is toward the rear of the machine and at a point slightly outward from the seam-line, and swings across the needle path and forwardly through somewhat more than a quadrant of rotation to bring the shoulder 81 75 finally to a position on the opposite side of the needle and slightly inward from the stitch line, or inwardly beyond the crest of the presser-foot. Thus the main looper hook starting from the position as diagrammed in Fig. 7 will take the loop of needle thread as indicated in Fig. 8, and carry it (during the time that the feed is occurring) over to position indicated in Fig. 9, and in substantially this last position the main looper member should dwell until the vertically vibrating looper member 49 may be moved downward to take, and spread, the needle-thread loop and present it at a low enough elevation to receive the needle on the next penetrating thrust of the latter. For simplicity of construction the vertically vibrating or secondary looper member may be given a direct vibration from a simple eccentric. Such looper member is formed as a generally upright rod or finger 83 having a point 84 terminating at its upper end in a shoulder 85, this looper rod structure being secured in a vibrating lever arm 86 which is pivoted as at 87 to the frame member 42 and which has its opposite end pivotally connected to rod 88 of the eccentric strap 89 which in turn engages the stated eccentric 51. The connections between the vertically disposed rock-shaft 90 for the main looper member 48 and the operating link 65 for imparting motion thereto, should be such as to cause a dwell in the operation of the main looper when it is in its forwardmost position shown in Fig. 9, and also it should accommodate the rise and fall of the looper bar commensurate with movement of the presser-foot as heretofore described. In the specific construction shown, therefore, I employ a crank 91 upon the upper end of the looper rod 90 and to its 105 crank beam 92 I pivotally connect one extremity of link 93 of a toggle lever, the other link 94 of which, pivotally connected to link 93, I pivot at its opposite end to bracket 95 carried by the frame arm 40. To permit the rise and fall of the looper-rod I make one 110 of the toggle links in two pieces pivoted together on a horizontal axis as at 97, and the pivot pin 98 connecting the two links 93 and 94, I employ as the point of pivotal connection of the end of link 65.

The effective action of the toggle lever motion for actuating the horizontally swinging main looper member is illustrated in Figs. 7 to 11. The reciprocatory motion of 130

link 65, imparted to it by the bell-crank and link connections 56 and 53 from the eccentric 50, will be translated into a differential-speed oscillation of the main looper member 5 that will include a dwell of the main looper to permit of easy loop-transference to the secondary loop transferer 49, thus as the link 65 pushes leftward from the position shown in Fig. 6, it will rapidly move the 10 main looper member through its loop-taking excursion, and continue the movement of the main looper with decelerating speed until the toggle links come nearly to a line of dead-center, when effective motion of the 15 main looper will cease. During the period of movement of the actuating link 65 from the position shown in Fig. 9, to one side of dead-center of the toggle link structure, until the toggle links have been thrown over 20 dead-center to the position shown in Fig. 10, and brought back again to position indicated in dotted lines in Fig. 10, the main looper element will substantially stand still, its very slight incidental movement being function- 25 ably negligible.

The two eccentrics 50 and 51 are so timed that the vertically vibratable secondary looper 49 descends as the needle is starting its forward excursion, and lowers and 30 spreads the loop that has been carried across the seam line by the main looper, so that as illustrated in Fig. 10, it presents the loop to be passed through by the needle before the latter penetrates the work, the main looper 35 and secondary looper then successively disengaging themselves from the loop to leave it positioned upon the needle, subject to the seating of the stitch by means of the take-up member 60, on the subsequent retraction of 40 the needle.

It will be observed that the accurate positioning of the needle during the working period of its reciprocation, the constant maintenance of practically uniform conditions in the handling of the thin material between the feed wheel and the presser-foot and the maintenance of a sharp bend in the work at a constant level, are all conductive to ability to handle the thinnest materials 45 and of stretchable nature, ordinarily difficult of manipulation in a blind stitch machine; while the simple and effective mechanisms for imparting movement to the needle-bar and looper members are conducive to 50 high speed of operation. Manifestly the particular character of looper mechanism, sub-divided into two simple parts, each traveling in a single plane of, respectively, horizontal oscillation and vertical vibration, insures the presentation of a large and ample 55 loop, with practical elimination of possibility of loop-failure, and further, this mechanism coordinates most advantageously with the character of feeding mechanism employed, 60 that requires a very substantial lowering of

the loop from the point where the loop is taken to the point where it is presented to receive the needle, the narrow, sharply-angled formation of the presser foot giving clearance for the secondary looper operation. 70

While I have described in some detail a particular embodiment of my invention for purposes of full disclosure, it will be apparent to those skilled in the art that many changes in details may be made without departure from the spirit of my invention within the scope of the appended claims. 75

I claim:

1. In a blind-stitch sewing machine, the combination of a presser-foot having a work opening, a bender therebelow, definitely positioned to present a work bend always at the same point, means for raising the presser foot, a needle for reciprocation across the presser-foot work opening, and a 80 chain-stitch looper comprising a main looper member oscillatable in a horizontal plane above the needle, and a secondary member vibratable in a plane at right angles to the first to take the loop from the first 85 said member and depress and spread it, said main looper member being vertically displaceable with the presser foot, and said secondary member being fixed against movement with said presser foot. 90

2. In a blind-stitch sewing machine, the combination of a presser-foot having a work-opening, a bender therebelow and co-acting therewith to present a work-bend therethrough, and stitch-forming mechanism working above the presser-foot comprising a reciprocating needle, a main looper hook mounted to oscillate in a horizontal plane, means for imparting to said main looper member motion at a variable rate to 100 give a dwell at the end of its loop-carrying excursion and including a crank connected with the main looper member, a fixed bearing stud, a jointed toggle-lever connecting said crank and stud, and actuating means 105 connected to the joint of said toggle lever; an auxiliary looper member mounted for movement of its active, lower end substantially up and down from position above to position below the plane of operation of the looper hook, for expansion of the loop 110 chiefly in a vertical direction, and means arranged and adapted to vibrate said secondary looper, depressing it to take the loop 115 during such dwell in the motion of said primary looper. 120

3. In a blind-stitch sewing machine, the combination of a frame, a presser foot vertically movable therein and having an opening, work-presenting means below said presser-foot coacting with said opening, a needle reciprocable above said presser-foot, and a looper mechanism comprising a main looper member, operative connections between said main looper member and said 125 130

presser foot adapting them to be raised together, a crank connected with the main looper member, a toggle link structure for operating said crank including a vertically-
5 flexible link, and means connected with the toggle joint for vibrating the same to oscillate the looper member.

4. In a blind-stitch sewing machine, the combination of a frame having a base and
10 an overhanging arm, a presser foot carried by said arm, coacting work-handling and feeding mechanism carried by said base, a vibrating needle arranged above said presser foot, looper mechanism carried by said
15 overhanging arm including an oscillatable main member and a vibratable secondary member, a main shaft carried by said base, an eccentric thereon, a lever operated by said eccentric having operative connections
20 with the needle and the main looper member to actuate both thereof, a second eccentric on said shaft, and operative connections between said second eccentric and the secondary looper member.

25 5. A structure as set forth in claim 4,

wherein the needle-thread take-up is carried by the lever that actuates the needle.

6. In a sewing machine for blind-stitching very thin fabrics, the combination of a narrow presser foot having an angular 30 groove in its under side and a work opening, a bender working below said presser foot comprising a narrow, similarly angular member having a fixed position, a slender straight, horizontally-reciprocating needle 35 working above the presser-foot across its work opening, and coacting looper mechanism comprising a main looper member horizontally oscillatable to take the loop and a secondary looper member vertically 40 vibratable to take the loop from the first said member and depress it and spread it around the path of travel of the needle.

7. A structure as set forth in claim 6 wherein said presser foot is provided with 45 needle guiding recesses on opposite sides of the work opening, substantially as described.

HERMANN JÄNISCH.
